UNITED STATES PATENT OFFICE.

BENJAMIN F. AUFTERHEIDE, SR., OF DAVENPORT, IOWA.

SASH WEIGHT.

1,425,570.

Specification of Letters Patent.

Patented Aug. 15, 1922.

Application filed April 14, 1922. Serial No. 552,479.

To all whom it may concern:

Be it known that I, BENJAMIN F. AUFTERHEIDE, Sr., a citizen of the United States, residing at Davenport, in the county of 5 Scott and State of Iowa, have invented a new and useful Sash Weight, of which the following is a specification.

My invention relates to sash weights which are adapted to operating one or more 10 window sashes by a single weight; and the objects of my invention are, first, to provide a weight which is not liable to get stuck in the casing channel; second, to provide a weight which will facilitate the movement 15 of one or the other, or both sashes, in the desired direction without interfering with the other; third, to provide a weight capable of being readily made heavier or lighter to suit the varying weights of sashes; 20 fourth, to provide a single weight suitable to handling sashes of varying weights at the same time.

I attain these objects by the mechanism illustrated in the accompanying drawings, 25 in which—

Figure 1 is a side elevation of the sash weight, having a portion of one end cut away to disclose a side view of the mounted pulley, also showing the petty weights attached; Fig. 2 is an edge elevation of the sash weight, disclosing the operation of the end pulley and having a portion cut away to disclose the manner of mounting the petty weights; Fig. 3 is a plan view at 30 an angle, of a petty weight; Fig. 4 is a front view of the window, illustrating the manner of attachment and operation of the sash weight, without the petty weights; and Fig. 5, an edge view; Fig. 6 is a top plan 35 view of the sash weights, pulleys and window sash in operation.

Similar numerals refer to similar parts throughout the several views.

First, I provide a rectangular block 1, of 45 any desired width and thickness, composed of any suitable material, and having outwardly across each of its ends and along each of its edges, bevels 3^a, 4^a, 12 and 12^b, reaching to the center of said ends and 50 edges, the facet of said bevels being suitably sloping to facilitate the passage of the weight 1, upward and downward in the casing, when the channel of the casing is obstructed by any substances such as nails 55 or plaster and to facilitate its manufacture; it will, however, be observed that the

weight may be constructed with round or flat sides, edges and ends, or either, as desired.

In one of the ends of said block 1, I provide a bifurcated slot 2, of suitable dimensions to admit the proper introduction and installation therein of a pulley 7, between jaws 3 and 4, revolvably, on axle 6, which axle 6 is fixedly mounted in holes 5 and 5^a, 60 65 provided in said jaws 3 and 4.

Suitably distanced between the ends of block 1, transversely from side to side therethrough I provide a rectangular opening 8, having its jamb, lintel and sill inwardly beveled 8^a, from each side to center, and having arranged across it from one jamb 12^a to the other 12^b, saddle bars 10 and 11, each having their tops, 10^a and 11^a and the middle ones having their bottoms, 10^b, 70 75 80 11^b beveled to center, and having perpendicular sides, 10^b and 11^b to facilitate the easy mounting of petty weights, 13, loosely thereon, as illustrated in Figs. 1 and 2, as desired.

Said saddle bar 11 is made integral with end 12 and protrudes upwardly in opening 8 from sill 8^b. Saddle bars 10 and 11 are each made suitably narrower than the edges of weight 1, so that when a petty weight 85 13 is mounted thereon by means of its bifurcation 14, the petty weight may not be wider than the thickness of weight 1, as shown in Fig. 2.

The jamb, lintel and sill of opening 8 90 are also beveled 8^a to facilitate the easy mounting thereon or removal therefrom of petty weights 13.

Petty weight 13 consists of a rectangular block of any suitable substance of any 95 thickness desired and of a width corresponding to the thickness of weight 1, and its length is suited to the space between saddle bars 10 and 11, and has one of its ends bifurcated 14, to correspond to the thickness 100 of bars 10 and 11, said bifurcation having its inward end grooved 14^a suitably to correspond with the upper beveled edge 10^a of saddle bars 10 and 11, and as many of said petty weights may be used as occasion 105 may require.

I claim:—

1. A sash weight of rectangular dimensions, the surfaces of its edges beveled to center, one of its ends bifurcated, the said 110 bifurcated end supporting a pulley revolvably installed within such bifurcation by

axle means within holes provided in the jaws of said bifurcation; a transverse rectangular hole suitably disposed between the inward extremity of such bifurcation and the opposite end of such weight, said rectangular hole having its jamb, lintel and sill beveled to center, said rectangular hole having multiple saddle bar members disposed across it, one of which members 5 pro-
 trudes upwardly from said sill, the other 10 of said members being connectedly supported by the said jambs, said saddle bars having their edges beveled to center and perpendicular sides, a petty weight member 15 having a bifurcation in one of its ends capable of being mounted upon said saddle bars within said transverse opening, all further purposes specified.

2. In a sash weight of rectangular dimensions of any desired width and thickness, having its upper end bifurcated suitable for the installation of a pulley therein; said sash weight having, outwardly across each of its ends and along each of its 25 edges, bevels reaching to the center of such ends and edges, said sash weight also having transversely from side to side, a rectangular hole, said hole disposed nearer the end, said rectangular hole having lintels, 30 jambs and sills, each having beveled facets, said rectangular hole also having saddle bar members crossing it connecting said jambs, one of said saddle bars being integral with the end of said weight, set in from each 35 side of said end forming sills, protruding perpendicularly in said opening from such end, having its top beveled to center, the others having their tops and bottoms beveled to center, their sides perpendicular, each 40 saddle bar being suitably thinner than the thickness of the weight, to admit of the installation thereon of a thin petty weight within the line of said transverse hole; a petty weight installed upon one of said 45 saddle bars, said petty weight being thinner than its width, its width corresponding to the thickness of the transverse opening, of length suitable to be installed or removed between the saddle bars, by means of a 50 bifurcation provided in one end of said petty weight; the inner end of such bifur-

cation being conformable to the edge of a saddle bar.

3. In a sash weight of rectangular dimension, being wider than thick, having its 55 top end bifurcated through its widest dimension, suitable for the installation of a pulley therein and a rectangular transverse hole in its side disposed parallel with its longer dimension below said bifurcation; 60 said rectangular transverse hole having its side and top beveled to center, its bottom having spaced midway therein protruding upward from beveled sill portions, a saddle bar connectedly with its side walls; said saddle bar having perpendicular sides and having its top beveled to center; other saddle bars reaching across said rectangular transverse opening connectedly with its side 65 walls, said saddle bars having their upper 70 and nether sides beveled to center and having perpendicular sides; each of said saddle bars suitable for having installed thereon a petty weight having one of its ends bifurcated to conform to the dimensions of said 75 saddle bars.

4. In a sash weight of rectangular dimensions, being wider than thick, having a bifurcation suitable for the installation of a pulley, provided parallel with its widest 80 dimension, in its top end, and having a rectangular transverse hole through its side, below said bifurcation, and saddle bars arranged across said opening, capable of having a petty weight mounted thereon; a petty 85 weight of rectangular dimension, being wider than thick, and having a bifurcation provided in one of its ends, paralleling its narrower dimension, and of suitable length, having its side walls and top formed conformable to the formation of the said saddle 90 bars provided across said right angular transverse opening through said sash weight, said petty weights capable of being mounted, by means of said bifurcation, upon 95 said saddle bars, without any portion thereof extending outside of the lines of said rectangular transverse opening.
